UNITED STATES PATENT OFFICE.

CLARK ROBINSON, OF HARTLEY, IOWA.

WRITING-TABLET.

SPECIFICATION forming part of Letters Patent No. 368,972, dated August 30, 1887.

Application filed February 24, 1887. Serial No. 228,737. (No model.)

To all whom it may concern:

Be it known that I, CLARK ROBINSON, of Hartley, in the county of O'Brien and State of Iowa, have invented certain new and useful 5 Improvements in Writing-Tablets, of which the following is a specification.

My invention relates to that class of writing or sketching tablets in which a continuous sheet or roll of paper is employed; and 10 it consists in a novel construction of the same, as hereinafter fully set forth and claimed, whereby I am enabled to use both sides of the paper without removing it from the tablet.

In the drawings, Figure 1 is a perspective 15 view of my improved tablet, and Fig. 2, a longitudinal vertical section of the same.

A indicates a frame, comprising side bars, *a a*, and flat cross-pieces *b b'*, the latter being of a length less than that of the sides, and having 20 their flat outer faces preferably set below the top edges of the side bars, as shown in Fig. 1. This frame A will be constructed, preferably, of wood dressed and finished as desired, the outer faces of the cross-pieces or 25 paper-supports *b b'* being made smooth and even to afford a proper backing for the paper passing thereover.

At each end of the paper-supports *b b'* are small rollers *c c' c'' c'''*, which are journaled at 30 their ends in the side bars, *a a*.

Upon reference to Fig. 2 it will be noticed that the outer faces of the rollers project slightly above or beyond the paper-supports, so that the paper in being drawn over said 35 supports will not bear thereon except when writing. This is not essential, however, and, as it tends to hold the paper away from the backing, will not be used for tablets designed for nicer work.

40 At each end of the frame A, midway between the supports *b b'*, is a roller or shaft, indicated, respectively, by the letters B and B', upon which the continuous web or sheet, C, of paper is wound, the web passing from 45 the under side of roller B over roller *c*, backing or support *b*, and roller *c'*, thence backward between the supports *b b'*, around roller *c''*, over support *b'*, thence over roller *c'''* to the second paper-roll, B'.

50 The paper-rolls B B' may consist simply of

a shaft or rod having an enlarged milled head at one end and a nut at its other end, a short longitudinal slot being made in the shaft or rod between its ends. The end of the paper will be cut to a point and passed 55 through the slotted shaft.

I do not wish to be understood as limiting myself to any particular construction of the shafts or rollers upon which the paper is wound, as it is apparent that it is a matter 60 capable of considerable variation, and in no way affects the gist of my invention.

In turning the shaft or roller in the direction indicated the paper upon the support *b* will be drawn forward, and as it is written 65 upon it will be wound upon said shaft or roller. When all the paper is wound upon the roller B, the tablet is reversed, end for end and face for face, so as to make the roller or shaft B', from which the paper was unwound, 70 the winding-roller.

It will be noticed that as the web passes over the support *b* it exposes one side or face of the web; but when passing over the support *b'* the opposite face of the web is exposed, and from this construction it follows that I am enabled to utilize both sides of the paper for writing, a result not heretofore secured, so far as I am aware. 75

The rollers *c c' c'' c'''* cause the paper to feed 80 along smoothly, and present no sharp corners over which to draw the paper.

Having thus described my invention, what I claim is—

1. A reversible writing or sketching tablet comprising a frame, suitable paper-winding rollers, and a continuous web of paper extending from one roll to the other and arranged, substantially as shown, to expose opposite sides of the web on opposite faces of 85 the tablet.

2. In combination with a frame, a paper-feeding roller at each end thereof, two paper-supports arranged back to back to sustain the web, and having their opposing faces separated from each other, and a continuous web passing from one roller over and between the intermediate paper-supports to the other roller. 95

3. In combination with sides *a a*, paper- 100

supports b b' , rollers c c' and c^2 c^3 , journaled at opposite ends of the supports, shafts B B' , journaled in the sides a a at the ends of the latter, and a web, C , secured at its ends to the shafts B B' and passing over the outer faces of the supports b b' , all substantially as shown.

In witness whereof I hereunto set my hand in the presence of two witnesses.

CLARK ROBINSON.
